(57) **CLAIM**

The ornamental design for a hospital gown, as shown and described.

DESCRIPTION

FIG. 1 is a front perspective view of the hospital gown of the present invention;

FIG. 2 is a front perspective view thereof, with the side opening in open position;

FIG. 3 is a back perspective view thereof, with the back opening in closed position;

FIG. 4 is a front elevational view thereof;

FIG. 5 is a back elevational view thereof;

FIG. 6 is a right side view thereof;

FIG. 7 is a left side view thereof;

FIG. 8 is a bottom plan view thereof; and,

FIG. 9 is a top plan view thereof.

The attachment snap fasteners shown in phantom in FIGS. 1-9, as well as the modeling patient shown in phantom in FIGS. 1-3, are all shown for illustrative purposes only and form no part of the claimed design.
